DESIGN FOR A CREAM SEPARATOR

Clifford E. Butler, Waterloo, Iowa

Application October 5, 1938, Serial No. 80,275

Term of patent 14 years

To all whom it may concern:

Be it known that I, Clifford E. Butler, a citizen of the United States, residing at Waterloo, in the county of Blackhawk and State of Iowa, have invented a new, original, and ornamental Design for a Cream Separator, of which the following is a specification, reference being had to the accompanying drawing, forming part thereof.

Fig. 1 is a front elevation of the cream separator, showing my new design.

Fig. 2 is a right side elevation thereof, parts illustrated in dotted lines in Fig. 1 being omitted.

Fig. 3 is a left side elevation thereof, parts illustrated in dotted lines in Fig. 1 being omitted.

Fig. 4 is a top plan view thereof, parts illustrated in dotted lines in Fig. 1 being omitted.

I claim:

The ornamental design for a cream separator, as shown.

CLIFFORD E. BUTLER.
